(57) **CLAIM**

The ornamental design for a toaster oven, as shown and described.

DESCRIPTION

FIG. 1 is a perspective view of a preferred embodiment of the toaster oven.

FIG. 2 is a front end view of the toaster oven shown in FIG. 1.

FIG. 3 is a rear end view of the toaster oven shown in FIG. 1.

FIG. 4 is a right side view of the toaster oven shown in FIG. 1.

FIG. 5 is a left side view of the toaster oven shown in FIG. 1.

FIG. 6 is a top plan view of the toaster oven shown in FIG. 1.

FIG. 7 is a bottom plan view of the toaster oven shown in FIG. 1.

FIG. 8 is a perspective view of another preferred embodiment of the toaster oven.

FIG. 9 is a front end view of the toaster oven shown in FIG. 8.

FIG. 10 is a rear end view of the toaster oven shown in FIG. 8.
FIG. 11 is a right side view of the toaster oven shown in FIG. 8.
FIG. 12 is a left side view of the toaster oven shown in FIG. 8.

FIG. 13 is a top plan view of the toaster oven shown in FIG. 8; and,
FIG. 14 is a bottom plan view of the toaster oven shown in FIG. 8.
